UNITED STATES PATENT OFFICE

GEORGE W. BLANK, OF NEWARK, NEW JERSEY

TOY

Application filed May 28, 1931. Serial No. 540,522.

My invention relates to a new and amusing toy and has for one of its objects to provide a device of this kind which may be operated by one or both hands of a person, such as a child, to imitate the puffing sounds of a locomotive.

Another object of the invention is to provide a toy of this kind having a whistle mounted thereon whereby locomotive signals may be imitated.

A further object of the invention is to produce a toy consisting of two members slidably mounted relative to each other and each member carrying an abrasive material which will rub against each other at intervals during reciprocation of one of the members relative to the other, whereby sounds in imitation of the puffs of a locomotive will be produced.

With these and other ends in view, this invention consists in the details of construction and combination of elements hereinafter set forth and then specifically designated by the claims.

In order that those skilled in the art to which this invention appertains may understand how to make and use the same, I will describe its construction in detail, referring by numerals to the accompanying drawings forming a part of this application, in which:

Fig. 1 is a side elevation of a toy constructed in accordance with my invention and illustrating one of the slidably mounted reciprocating members adjacent the extreme end of one of its movements.

Fig. 2 is an end view thereof looking at the right hand end of Fig. 1.

Fig. 3 is a section on the line 3—3 of Fig. 1.

Fig. 4 is a side elevation similar to that of Fig. 1, showing another form of the invention.

Fig. 5 is an end view of Fig. 4.

In carrying out my invention as herein embodied, 6 and 7 represent two similar members which are preferably oblong strips of wood or other material which is the equivalent of wood for the purpose herein shown and described.

One of the members, as 7, may have longitudinal grooves 8 in the opposite longer edges

with which register the inturned toes or flanges 9 of the guides 10 which are fastened to the other member, as 6, by means of suitable fastening devices 11, such as screws. Considering the elements 10 as guides, the 55 grooves 8 will be the guideways but of course, it is understood that any other suitable means of slideable connecting or associating the reciprocating members in spaced relation can be utilized.

The reciprocating movements of the two members longitudinally relative to each other can be limited by stops 12 consisting of some deadening material, such as rubber, placed in the path of travel of the guides 10, or one of them, at both ends of the other member. As herein illustrated, these stops are small pieces of rubber placed in the grooves or guideways 8 and held in place by tacks or nails 13 passing through the pieces of rubber and projecting into the member on which they are mounted.

On the inner face of each member is mounted a piece or strip of abrasive material 14, such as emery cloth, sand paper or any equivalent thereof and the abrasive material on one member is in the path of travel of the abrasive material on the other member and therefore are located within the space between the two members. For a purpose 80 which will become apparent from the later description, the abrasive materials are placed to one side of the device although they can be otherwise located when convenient so long as one is in the path of travel of 85 the other.

In order that the abrasive materials may have a rubbing contact and yet may readily pass each other during the reciprocations of the members, said abrasive materials are backed up by or the said abrasive materials are disposed over cushions 15 of any suitable compressible material, such as felt, rubber, springs or equivalent means and the abrasive strips may be held in place by tacking the 95 ends thereof to their respective members, the tacks being indicated at 16.

So far both forms of the invention illustrated are identical with each other and therefore the same reference numerals have 100

been used to indicate like parts in the drawings.

Where it is desirable to include other sound means such as a whistle, one of the members is provided with a recess 21 in which the pipe portion or body of the whistle 17 as well as a part of the bulb 18 may be located, said bulb forming a part of the whistle in that the collapsing thereof will force air therefrom into the whistle body and produce whistling sounds.

The other member, as 7, is provided with a channel 19 in its inner face which may run only a short distance although if more desirable from a manufacturing standpoint, said channel may run from end to end. This channel provides the necessary clearance for the whistle bulb where it is necessary that said bulb pass inside of the end of the member opposite the member which carries the whistle.

It might be well to state at this time that if the two members are spaced apart a sufficient distance it will be unnecessary to provide the recess for the reception of the whistle body or provide the channel for clearance of the whistle bulb. The converse of the above is that with the members spaced relatively as shown, the whistle and its bulb or operating means for the whistle can be small enough to fit within the two members.

While the toy may be held in the hands and one member gripped by each hand and then slid back and forth or reciprocated, it is even more convenient to rest the toy upon a supporting surface, such as a table or desk or even the floor and then by the use of one hand move only one member. In such a case, it is advisable to provide means to prevent the toy from slipping about and to this end I place friction strips 20 on the outside surface or bottom of one of the members, as 7 and these friction strips or elements may be corrugated or otherwise roughened material or some kind of material that will produce a "drag" or a slight suction on a supporting object.

The construction, arrangement or location of the parts relative to each other must be such that the abrasive materials will contact with each other and then pass beyond one another at or near the end of each movement of the members, in other words, there is a period when the two abrasive elements produce a scraping or puffing sound and another period directly thereafter when there is no sound so that there is a period of silence between two periods of sound.

It might be said that when the device or toy is properly operated for producing sounds in imitation of locomotive puffs, the members, or one of them, are reciprocated so that the abrasive materials contact with and pass each other during each movement thereby producing periods of sound between alter-

nate periods of silence and by properly placing two fingers of the hand resting on the member carrying the whistle, in contact with the bulb of said whistle, the latter may be sounded as desired in imitation of locomotive whistle signals.

Since the toy has fairly large smooth surfaces exposed, pictures of different kinds, such as pictures of locomotives or trains may be delineated thereon and railroad whistle signals may be shown on one of the surfaces.

Of course, I do not wish to be limited to the exact details of construction herein shown and described as these may be varied within the limits of the appended claims without departing from the spirit of my invention.

Having thus fully described my invention, What I claim as new and useful is:

1. A toy consisting of two members slidably mounted in spaced relation to each other and abrasive materials on the inner surfaces of said members for contact with each other, the contacting portions being of less length than the lengths of the movements of the members relative to each other whereby the full reciprocations of said members will produce a period of sound between alternate periods of silence.

2. The structure set forth in claim 1, in combination with means for cushioning the abrasive materials.

3. A toy consisting of two members slidably mounted in spaced relation to each other and an abrasive material on the inner surface of each member of less length than the member and located midway between the ends thereof.

4. A toy consisting of two slidably connected members and abrasive materials on the inner faces of said members for contact with each other as they pass by one another, the combined lengths of the contact surfaces of said abrasive materials being less than the length of either of the members.

5. The structure set forth in claim 4, in combination with cushions mounted between the abrasive materials and their respective members.

6. A toy consisting of two similar oblong members, means for slidably connecting said members together in spaced relations, an abrasive material on the inner surface of each member for contact with one another during certain periods of the reciprocations of the members, means to limit the reciprocating movements of the members and friction material on the outer surface of one of said members.

In testimony whereof, I have hereunto affixed my signature.

GEORGE W. BLANK.
